United States Patent Office.

R. R. FENNER, OF URBANA, ILLINOIS.

Letters Patent No. 91,617, dated June 22, 1869.

IMPROVEMENT IN STUBBLE AND SUBSOIL-PLOW.

The Schedule referred to in these Letters Patent and making part of the same.

To all whom it may concern:

Be it known that I, R. R. FENNER, of Urbana, in the county of Champaign, and State of Illinois, have invented a new and improved Plow; and I do hereby declare that the following is a full and exact description thereof, reference being had to the accompanying drawings, and to the letters of reference marked thereon.

Figure 1 is an upright perspective view of my invention, from the landside.

Figure 2 is a back view of fig. 1.

Figure 3 is a plan view, the dotted lines showing the two extremes to which the beam can be thrown.

Figure 4 is an elevation of the diagonal slotted T-piece, or guide-plate.

Figure 5 is a transverse sectional view on the line x x of fig. 1.

Figure 6 is a transverse sectional view on the line y y of fig. 2.

Similar letters of reference indicate like parts in all the figures.

This invention relates to stubble and subsoil-plows; and

It consists in the construction and combination of its various parts, as herein described and claimed.

A is the beam.

B is the landside.

C is the mould-board.

Lugs, d d', are constructed or cast, in the process of manufacture, on the landside of the plow, as shown in fig. 5. The standard D, which supports the beam A and its adjuncts, slides vertically within the groove, or channel thus formed.

The shaft D' passes through a portion of the bed-plate E, projecting inward from the beam A, said shaft having, upon either side of the said projection, rings, firmly soldered or otherwise fastened thereto.

The lower portion of the shaft has a screw-thread surface, which plays through the screw-thread eye e, said eye being firmly embedded in the landside of the plow, as shown in fig. 1.

The beam A has a free lateral swing on the standard-bolt f.

F is a metal plate, covering the end, upper and lower sides of the beam. Projecting from this plate is the threaded rod g, passing through the upper slot of the guide-plate G.

g¹ is a ring, placed over the rod g, while

g² is a threaded hand-wheel.

H is a metal plate, having flanged edges, and is at-

tached to (or it may be constructed with) the cross-bar I. Within the flanges of this plate slides the lower portion of the guide-plate G.

The hand-wheel h has a threaded rod, which passes through the vertical slot, and is fastened by a screw-nut.

The upper portion of the guide-plate is convex in form, to adapt itself to the changes in the position of the beam.

When it is desired to have the plow take more land, the hand-wheel g² should be loosened, and the front end of the beam pushed inward. To take less land, it should be directed outward. Thus the width of the furrow becomes easily regulated.

If the plow runs too deep, loosen the hand-wheel h, then lower the beam, by turning the shaft D' to the right, and fasten the hand-wheel h as before. If the plow does not run deep enough, perform the same operation, except you raise the beam.

As indicated by the title, my invention can be adjusted for use as a subsoil as well as for a stubble-plow.

When you wish to subsoil a piece of ground, set the plow as for stubble or old ground, plow once around the land, then raise the beam to a sufficient height, and plow again in the same furrow; change back to stubble, and so on alternately, adjusting from stubble to subsoil, until the work is completed.

My invention is adapted to light ditching and all kinds of plowing, and as such especially commends itself for its convenience, as well as its economy, to the judicious farmer.

Having thus described my invention,

What I claim, and desire to secure by Letters Patent from the United States, is—

1. The combination of the shaft D', bed-plate E, standard D, eye e, with the landside of a plow, for the purpose of raising or lowering the beam, substantially in the manner herein shown and described.

2. The combination of the guide-plate G, threaded rod g, and plate H, for the purpose of giving the beam a lateral motion, substantially as and for the purpose herein shown and described.

In testimony whereof, I have signed my name to this specification, in the presence of two subscribing witnesses.

R. R. FENNER.
